UNITED STATES PATENT OFFICE.

FEITZ REICHARD, OF ESSEN, GERMANY, ASSIGNEE TO FRIED. KRUPP AKTIEN-
GESELLSCHAFT, OF ESSEN-ON-THE-RUHR, GERMANY.

TUBBING FOR SHAFTS.

Application filed February 14, 1921. Serial No. 444,846.

To all whom it may concern:

Be it known that I, FRITZ REICHARD, residing at Essen, Germany, a citizen of the German Republic, have invented a certain new and useful Improvement in Tubbing for Shafts, of which the following is a specification.

This invention relates to the tubing of shafts and has for its object to provide tubbings possessing not only a high power of resistance to the all-round lateral earth pressure, but also an increased resisting capacity to the stresses caused by bending moments.

The invention will be further described with reference to the accompanying drawing which shows, as an embodiment of the subject matter of the invention, a wrought iron tubing by way of example.

In the drawing—

Fig. 1 is a view, partly in section, of a single shaft ring, looking in a diametrical direction, and

Fig. 2 is a view, partly in section, on line 2—2 in Fig. 1, disclosing half of the shaft ring, seen from above.

Referring to this drawing, the shaft rings are composed of single arcuate sections connected to each other at the joints A. Each arcuate section substantially consists of an external boom plate B and an internal boom plate B¹ (each of which forms part of a cylindrical shell), as also of two web plates C connecting the boom plates B and B¹, and having the shape of an annular sector and angularly flanged at their outer edges. These four plates are connected to each other so as to constitute an arcuate box girder. The web plates C are provided with openings c¹ and project in the direction toward the interior of the shaft beyond the internal boom plates B¹ which are completely lodged between them and moreover form, by their edge portions c² extending into the interior of the shaft and connected by angle irons to the internal boom plates B¹, the flanges intended for the connection of the shaft rings to each other. The walls of the box-shaped structure forming each arcuate girder are interconnected by a plurality of reinforcing plates D, shaped by stamping and distributed along the whole length of the girder. Said reinforcing plates D are likewise provided with openings d¹.

The hereinbefore-described shaft rings are

built in by the arcuate portions being singly inserted in the shaft, where they are connected up to the arcuate portions adjoining them above and at the side. The openings formed in the web plates and in the reinforcing plates facilitate the assembling operation and moreover afford the possibility of filling the hollow portions of the girder with cement, if desired.

The improved form of tubing distinguishes itself from the known forms of tubing by increased strength. For as the all-round acting lateral earth pressure does not act uniformly upon the entire circumference of the shaft, the cross section of the ring is not only subject to compression, but, in addition, bending stresses come to work which are liable to attain very high values. The width of the box girders resulting from the distance between the two boom plates B and B¹ of the improved shaft ring offers an increased resisting capacity against the said bending stresses. This strength of the tubing is still further enhanced by the reinforcing plates D which effectually prevent a deformation of the rectangular cross section of the box girder. The mutual position of the shaft rings is besides specially safeguarded by the fact that the connection of the flanges c², serving to rigidly unite the shaft rings among each other, with the box girder offers a very high resisting capacity, and this owing to the fact that said flanges form a part of the web plates C which latter project towards the interior of the shaft.

Claims.

1. A shaft tubing formed in rings, each ring comprising a multiplicity of box-shaped girders, each girder comprising spaced external and internal boom walls and web walls connecting said boom walls at the top and bottom and coherent therewith along their whole length without interruptions.

2. A shaft tubing formed in rings, each ring comprising a multiplicity of box-shaped sheet metal girders, each girder comprising spaced boom plates, web plates connecting said boom plates and projecting toward the interior of the ring and beyond the internal boom plates.

3. A shaft tubing formed in rings, each ring comprising a multiplicity of box-shaped girders, each girder comprising an

external and internal boom plate, web plates connecting said boom plates and flanged reinforcing plates secured at spaced intervals in said hollow girders.

3 4. A shaft tubing formed in rings, each ring comprising a multiplicity of arcuate girders, each girder comprising spaced parallel boom plates, flanged arcuate web plates connecting said boom plates at their ends 10 and forming a box-shaped structure, said web plates extending beyond the boom plate disposed toward the interior of the ring and

reinforcing plates formed with flanges at their edges disposed at spaced intervals along the interior of said box-shaped girders. 15

The foregoing specification signed at Essen, Germany, this 15th day of December, 1920.

FRITZ REICHARD.
